GROUND-WIRE CLAMP

Julian Rogoff, New York, N. Y., assignor to
Burndy Engineering Co., Inc., a corporation of
New York

Application December 15, 1936, Serial No. 115,929

1 Claim. (Cl. 24—243)

My invention relates to ground-wire clamps, and more particularly to means for connecting electric conductors to ground rods.

In utility grounding practice, it is often customary to drive a copper coated steel rod into the ground and attach ground wires or cables to the rod by means of a clamp.

Up to the present, clamps have been devised which used flexible bands to force the ground rod or pipe against a contact screw to which the conductor cable was electrically connected. In one of these prior clamps, the contact screw carries the current, and is preferably made of substantially pure copper because of its high conductivity. The contact screw threadedly engages a pressure bar which transmits the pressure from the flexible bands.

In another such clamp, the contact screw again is used to ground the current, and therefore should be made of substantially pure copper to obtain proper conductivity. Pure copper is soft and has no yield point, and undue pressures cause the metal to "creep" and loosen the connection. Electrical contact was the important aspect of this invention, and consequently no great pressures were or could be developed.

To overcome the weakness inherent in devices which rely on current transmission through a contact screw, clamps were developed which utilized high pressures between ground rod and cable.

Thus connectors were developed having pressure members which, it was assumed, did not carry all the current, and which, by our corollary, could be made of an alloy having high tensile strength and thus allow pressures greatly in excess of those permitted by pure copper members which carry current.

Where the construction is as rugged as possible to permit the maximum pressure, the electric contact between cable conductor and ground rod is the only contact relied on and is established solely by pressure between the rod and conductor.

Where the device has been adapted to permit lateral entrance to a continuous cable, the plurality of parts found necessary are awkward to handle for a rubber-gloved linesman, or they are not readily accessible because they accidentally fall apart during shipment or handling.

Accordingly, a primary object of my invention is to provide a ground clamp for causing an electrical contact between an electric conductor and a ground rod, the component parts of the clamp structurally adapted to produce high pressures and the electrical conductivities of these component parts being sacrificed for mechanical strength.

Another important object of my invention is to provide a ground clamp capable of being slipped over a ground rod or continuous conduc-

tor, and which though it may be disassembled into its component parts, is normally interlocked during shipment and handling.

Another object of my invention is to provide such a clamp which will lend itself to economical manufacture by high speed production methods.

A further object is to provide a high strength corrosion-resistant clamp which can be stressed to high values in installation and buried directly into the ground without fear of failure. Still another object is to provide centering means for ground rod and cable so that maximum pressures can be applied and developed between the two.

I accomplish these and other objects of my invention by providing a U-shaped member, a novel pressure bar for engagement with the U-shaped member and a pressure screw for applying the pressure, none of which members are designed to carry electric current. All parts are designed to produce the maximum amount of pressure, and copper alloys are used only to avoid galvanic action between the clamp and the conductor, and to make the clamp corrosive-resistant in general. In addition I provide a design which normally keeps the parts interlocked and acting as a single unit when not in use. The interlocked members may be separated when it is desired to install the clamp on a ground rod or continuous cable, and attachment is made with the assurance that all necessary parts are available and readily accessible.

I attain my objects and accomplish my results as can be readily understood from a consideration of the accompanying description taken together with the drawing, in which:

Fig. 1 is a side view of my clamp assembled on a ground rod and conductor.

Fig. 2 is an end view of the same assembly.

Fig. 3 is a sectional view with the parts separated to permit entrance of the ground rod and conductor.

Fig. 4 is an end view of an assembled clamp, ground rod and conductor, with a protective washer inserted between the pressure screw and conductor.

Fig. 5 is a side view of the same.

Fig. 6 is a side view of the assembled clamp, ground rod and conductor, with a protective pressure plate rotatably mounted on the end of the pressure screw.

Fig. 7 is an end view of the same.

Fig. 8 illustrates the interlocking feature of the component parts of the clamp when not in use.

Fig. 9 illustrates a separation of the interlocking members to provide an entrance for ground rod and conductor.

Referring to Fig. 1, the clamp consists of a sheet metal body 11, a forged or extruded pressure bar 12, and a pressure screw 13. The pres-

sure screw 13 and the pressure bar 12 are assembled into unitary relationship by striking the end 14 of the screw 13 in order to damage the last thread. The sheet metal body 11 is bent into 5 the form of a U with a V-shaped bottom 15 as an aid in centering the conductor cable 16 or ground rod 17 which may rest therein.

The two legs 24, of the U-shaped member 11 are provided with two trapezoidal shaped apertures 18 allowing for movement of the round ends 21 of the pressure bar 12. On the upper surface of the pressure bar 12, grooves 19 are provided which interlock with the upper edge 20 of the apertures 18.

15 As illustrated in Figs. 3 and 9, in order to release the pressure bar and screw from the clamp, it is first necessary to rotate the pressure screw 13 outwardly from the U. The pressure bar 12 is then released from the upper edges 20 of the 20 apertures 18 and inserted as far as it will go into one of the apertures. This will free one end of the pressure bar, so that the bar may be removed by simply sliding out through the open end of the U. In order to facilitate this process, the ends of 25 the pressure bar are rounded or tapered, as at 21, leaving the central portion, where the bending movement is greatest, thicker than the two ends. The parts are so proportioned, however, that in order to prevent accidental disassembly in shipping or handling, the pressure screw 13 need 30 simply be threaded part way or entirely into the pressure bar 12 and towards the bottom of the U, whereupon the bottom of the screw will strike against the sides of the U and prevent the pressure block from disengaging from the U as illustrated in Fig. 8.

Figs. 4 and 5 show the same assembly as Figs. 1, 2 and 3, with the exception that washer 22 has been added to prevent the end 14 of the screw 13 from bearing directly on the cable 16, when it is 40 located above the rod, thus protecting the cable from abrasion or nicking by the revolving pressure screw 13. Washer 22 contains two punched out sections 23, which permit the two legs 24 and the U clamp 11 to enter. The washer is shaped 45 as at 25 to permit the conductor 16 to be centered within the clamp.

A method of protecting the ground rod from abrasion or nicking when it is on top, is shown 50 in Figs. 6, 7, 8 and 9. Here pressure plate 30 is attached in rotatable relationship to the end 14 of the screw 13, and acts as an integral part of the pressure screw and pressure block assembly. Thus, when the connector is taken apart, as 55 shown in Fig. 9, there are only two sections to handle. Pressure strip 30 consists of two end wings 33 which are curved to fit the upper rounded surface of the ground rod and a flat section 32 into which the end 14 of the pressure screw 13 is 60 mounted. The cut-out portions 31 allow the pressure screw and pressure block assembly to move towards the trapezoidal holes 18 without striking the pressure strip 30 against the sides of the U clamp.

65 It is apparent that an assortment of conductor sizes can be accommodated in a single sized clamp.

Each of the foregoing embodiments of this invention have the distinct advantage of being 70 made up of low cost elements, the constituent parts in the simplest form being simply a screw, a sheet metal stamping, and an extruded or

forged bar. Each of these parts is made by mass production methods in highly specialized machines, which means a minimum tooling up expenses, as well as a low unit cost. In addition, because of the minimum of cutting necessary to be 5 done in the parts, high strength, highly corrosive-resistant copper alloys can be economically used for all the parts, in spite of the fact that such alloys are very difficult to machine. Alloys having the following composition are recommended for strips, pressure screw plates and bars:

98% copper, 1 1/4% silicon, and 1/4% manganese, having a tensile strength of from 85,000 to 100,000 per square inch, the tensile strength being 15 sufficient to produce a distortion of the surface of the electric cable coming in contact with said ground rod.

In my invention, once the screw is threaded 20 entirely into the block, the assembly cannot work its way free from the sheet metal body. On the other hand, when it is desired to take the connector apart, this can readily be done with only two pieces to handle. It is significant that this may be done even though the height of the holes 25 punched in the sheet metal body is less than the thickness of the pressure bar. This may be an important advantage inasmuch as the less metal is punched from the U, the stronger is that part. This invention also makes possible the use of a 30 pressure plate to prevent abrasion of the conductors and to distribute the pressure evenly without the addition of another part to handle when the connector is taken apart.

Applicant's device distinguishes from all prior 35 art devices in that the U-shaped member is substantially rigid and is not adapted to change its shape to conform with the ground rod or cable supported therein. Provision is also made for centering the cable and rod with respect to each 40 other, so that the maximum pressures may be developed by the centrally located pressure screw, whether applied to rod or cable.

I have thus described my invention, but I desire 45 it understood that it is not confined to the particular forms shown and described, the same being merely illustrative, and that the invention may be carried out in other ways without departing from the spirit of my invention, and, therefore, I claim broadly the right to employ all 50 equivalent instrumentalities coming within the scope of the appended claim, and by means of which, objects of my invention are attained and new results accomplished, as it is obvious that the particular embodiments herein shown and 55 described are only some of the many that can be employed to attain these objects and accomplish these results.

I claim:

A connector comprising a substantially rigid 60 U-shaped member having an aperture in each of the two legs of the U-shaped member; a pressure screw; and a pressure bar for engagement with each of the apertures in the U-shaped member, said pressure bar having a central threaded aperture for said pressure screw and rounded ends to 65 facilitate entrance through the apertures in the legs of the U-shaped member which ends are curved in substantially the same direction as the U-shaped member.

JULIAN ROGOFF.
